UNITED STATES PATENT OFFICE.

SETH WHEELER, OF ALBANY, NEW YORK.

PACKAGE-WIRING MACHINE.

No. 921,193.

Specification of Letters Patent.

Patented May 11, 1909.

Application filed May 22, 1900. Serial No. 17,575.

To all whom it may concern:

Be it known that I, SETH WHEELER, a citizen of the United States of America, and resident of Albany, in the county of Albany and State of New York, have invented certain new and useful Improvements in Package-Wiring Machines, of which the following is a specification.

My invention relates to package wiring machines and particularly to machines for inserting wire fasteners into and through packages, such as packages of toilet paper or the like, and for bending over the projecting ends of the wire fastener.

To this end my invention consists in means for rotating a wire fastener, the end of which has been cut obliquely or has been otherwise sharpened, and in simultaneously thrusting the same through the package.

My invention also consists in improved means for bending over the projecting ends of the wire fastener after it has been inserted into and through the package.

Prior to my invention it has been customary to make an opening through the package for the wire before inserting it. By giving the end of this fastener a cutting edge and rapidly revolving it, it makes its own opening, and the package is wired in the same time or less than that required by the old method to make the opening, and far more easily, as considerable power is required to puncture so large an opening as the necessarily heavy stabber makes; while the rapidly revolving wire is passed through with a very slight expenditure of power.

My invention further consists in certain novel details of construction and combination of parts as shall hereinafter be more fully set forth.

I will now proceed to describe a package wiring machine embodying my invention in detail and will then point out the novel features in claims.

In the drawings, Figure 1 represents a side view of a package wiring machine embodying my invention; Fig. 2 represents a front view of the same. Fig. 3 is a horizontal section of the same. Fig. 4 is a detail view of certain formers employed and their actuating mechanism. Fig. 5 is a detail view of one of the wire fasteners employed, in its preferred form.

Similar reference characters designate corresponding parts in the several figures.

The frame of the machine is represented

as provided with a suitable base 5, a pedestal 6 rising from said base, an intermediate supporting frame 7 and a top head 8. The top head 8 carries a vertical shaft 9, which is suitably journaled in bearings in the said head 8. A pulley, or band wheel, 10 is secured to rotate with the shaft 9, but is arranged to have a relative movement longitudinally thereof, a shaft spline connection therewith, permitting such movement.

Reference character 11 designates a shift rod arranged to have a movement in the direction of its length and suitably housed in the rear of the head piece 8. The shift rod 11 is secured to the shaft 9 by means of a cross bar 12 which is rigidly secured to the top of the rod 11. The top end of the shaft 9 is mounted in the said cross bar, and is permitted to rotate freely therein, but, longitudinally, will partake of its movement.

Secured to the lower end of the shift rod 11 is a connecting rod 13. A treadle 14 is mounted in the pedestal 6 and a link 15 connects the movable end of the treadle with the connecting rod 13. A spring 16, secured at one end to the frame, is attached at the other end to the link 15 and tends normally to draw the vertical shaft, the shift rod and the treadle 14 upwardly. A drive shaft, having drive wheels 17, is mounted upon the pedestal of the machine and mounted upon the said shaft is a band wheel 18. A belt or band 19 passes around the band wheel 18, over idler pulleys 20 mounted upon studs secured to the head piece 8 and around the band wheel or pulley 10.

Power being applied to one of the wheels 17, the pulley 18 is caused to revolve, and motion will be transmitted to the band wheel 10. Consequently, motion will also be transmitted to the shaft 9. Upon depressing the treadle 14, the shaft 9 will be drawn downwardly, but its rotary motion will not be interfered with, because of the spline connection between it and the said pulley. The shaft 9 will be brought downwardly against the resistance of the spring 16 and will be returned to its upper position as shown in the drawings in Fig. 1, when the pressure upon the treadle 14 is removed. The lower end of the shaft 9 is provided with a chuck 21 having a slot 22 which is adapted to receive the looped end of a wire.

23 designates a table or platform which is secured to the intermediate frame 7 of the machine by suitable clamping bolts. The

holes in the extension of the platform or table, through which these clamping bolts pass, are preferably slotted, as shown at 24 in Fig. 2. These slots are so arranged, in order that the platform or table 23 may be correctly adjusted as to height. An adjusting screw 25 is provided for the purpose of supporting and adjusting the said table, the clamping bolts being loosened during the operation of the 10 adjustment and again tightened to securely clamp the said table in position. The table 23 is provided with a suitable gage 26 secured thereto, the purpose of which is to correctly locate the package upon the table when presented for wiring.

The operation of such portions of the machine as have been so far described is as follows: A package is placed upon the table 23 and located by being brought in contact at 20 the left hand side with the gage 26 and in front of the frame of the machine, the wire fastener with one end cut off at an angle, or sharpened, and the other end formed into a loop is held in position opposite the point at 25 which it is desired to insert the same in the package. This point will be in a line with the axis of the shaft 9. The shaft 9 will now be lowered and the loop of the wire engaged by the chuck 21, the wire loop will then partake of the rotary motion of the shaft 9, and, upon the shaft 9 being further depressed, the wire, by reason of its sharp point and its 30 rapid rotation, will be driven with but very little pressure through the package. The shaft 9 may now be permitted to return to its normal position and the wire will remain in the package with the loop extending above the package, and the end below the same. A top plate 27 is provided, and is shown as secured to the frame of the machine. The said top plate has a cut away portion 28 in the center to permit the passage of the wire loop. The end of the package is passed under this 35 plate when placed in position, as just described.

I will now describe the means for turning the loop down upon the top of the package, and for bending upwardly the end of the wire which extends through the bottom of the package. Reference characters 29 and 30 designate, respectively, upper and lower formers, which are secured to, or made a part of, short shafts mounted in the frame of the machine. Secured to move with the upper 50 former 29 is a lever 31, and secured to move with the lower former 30 is a lever 32. 33 designates a shaft mounted in brackets secured to the side of the machine, and 34 is an actuating handle or lever which is fast to the 55 said shaft. Levers 35 and 36 are loosely mounted upon the said shaft. The shaft 33 is provided with a pin or key 37 and the levers 35 and 36 have slotted keyways 38 and 39 in which the said key is arranged to 60 play. A spring 40, secured at one end to the

lever 35 and at the other end to the lever 36, tends to force the levers, at all times, to the position in which they are shown in Fig. 4. In such figure, the key 37 is shown as engaging with the right hand end of the slot 39 in 70 the lever 36, and with the left hand end of the slot 38 in the lever 35. A link 41 connects the free end of the lever 35 with the free end of the lever 32, and a link 42 connects the free end of the lever 36 with 75 the free end of the lever 31. If, now, the lever 34 be depressed, the key 37 engaging with the end of the slot 39 in the lever 36 will rotate the said lever, and through the link connection 42 and lever 31 will rotate the 80 former 29. The effect of this will be to bend the projecting looped end of the wire over the top of the package. The lever 35, by reason of the slot 38, will have remained stationary during this operation. The lever 85 36 will have been rotated against the action of the spring 40, and when the handle 34 shall have been released, the lever 36 and parts secured thereto will return to their normal position in which they are shown in 90 Fig. 4. Upon raising the handle or lever 34, the key 37 will pass freely along the slot 39, but will, by its engagement with the slot 38, rotate the lever 35. In so doing, the former 95 30 will be rotated and the lower extending end of the wire will be bent upwardly against the bottom of the package. The spring 40 will return these parts to their normal position in a similar manner as just described for the return of the former 29 and its actuating 100 mechanism.

It is obvious that many modifications of the mechanism herein described might be made without departing from the spirit and scope of my invention; I therefore do not 105 desire to be limited to the precise details of construction as herein shown.

What I claim is:

1. In a package wiring machine the combination with a table or support for the package, of a head having a chuck for receiving and holding a wire fastener, means for rotating the same relatively to the package and simultaneously thrusting the said fastener through the package, and for withdrawing the said chuck from engagement with the wire fastener after it has been thrust through the package, upper and lower formers for bending over the upper and lower projecting portions of the wire fastener after the same has been inserted, and means for moving the said formers across the axial line of rotation of the said head after the chuck has been withdrawn from engagement with the said fastener.

2. In a package wiring machine, the combination with a suitable table or support for the package, of upper and lower formers, a single operating lever and connections therefrom to both formers to operate same.

3. In a package wiring machine the combination with a suitable table or support for the package, of upper and lower formers, a single actuating lever and connections therefrom to the formers to independently operate each of the said formers.

4. In a package wiring machine the combination with a table and support for the package, of upper and lower formers for bending over the projecting ends of a wire which has been inserted into the package, an actuating lever, actuating mechanism connected to the upper and lower formers and to the actuating lever, the said actuating mechanism being so connected with the actuating lever that the movement of the said lever in one direction will operate the upper former, and the movement of the said lever in the opposite direction will operate the lower former.

5. In a package wiring machine the combination with a table or support for the package, of means for inserting a wire into and through the package, upper and lower formers for the bending over of the projecting ends of such wire after it has been inserted, actuating mechanism including a rotatable hub for each of said formers, an actuating lever having a part adapted to engage one of said hubs when moved in one direction and to engage the other of said hubs when moved in the opposite direction, and a spring connected with both of said hubs, opposing movement thereof.

Signed by me at Albany N. Y., this first day 25 of May 1900.

SETH WHEELER.
